UNITED STATES PATENT OFFICE.

AUGIE L. HANSEN, OF CHICAGO, ILLINOIS, ASSIGNOR TO JUSTRITE MANUFACTURING COMPANY, OF CHICAGO, ILLINOIS, A CORPORATION OF ILLINOIS.

DESIGN FOR AN ACETYLENE-LAMP BODY.

46,905.

Specification for Design.

Patented Feb. 2, 1915.

Application filed November 11, 1914. Serial No. 871,620. Term of patent 7 years.

To all whom it may concern:

Be it known that I, AUGIE L. HANSEN, a citizen of the United States, and a resident of Chicago, in the county of Cook and State of Illinois, have invented a new, original, and ornamental Design for an Acetylene-Lamp Body, of which the following is a specification, reference being had to the accompanying drawing, forming part thereof.

Figure 1 is a side elevational view show-

ing my new design, and Fig. 2 is a front view.

I claim:

The ornamental design for an acetylene lamp body, as shown.

AUGIE L. HANSEN.
